UNITED STATES PATENT OFFICE.

EUGEN ZBINDEN, OF WINTERTHUR, SWITZERLAND, ASSIGNOR TO BUSCH-SULZER BROS.-DIESEL ENGINE COMPANY, OF ST. LOUIS, MISSOURI, A CORPORATION OF MISSOURI.

CYLINDER AND HEAD CONSTRUCTION.

Application filed February 22, 1924. Serial No. 694,451.

To all whom it may concern:

Be it known that EUGEN ZBINDEN, citizen of Switzerland, residing in Winterthur, Switzerland, has invented the following described Improvements in Cylinder and Head Construction, for which he has filed applications for patent in Switzerland on February 20, 1923, and in Germany on February 21, 1923, respectively, Nos. 22,015 and 10 62,222.

The invention relates to cylinder and head construction. Its object is to simplify the construction and insure sufficient cooling adjacent the combustion space of the cylinder, 15 with a minimum metal stress due to difference in thermal conditions. To accomplish the object stated I provide the liner flange with a liberal longitudinal dimension and form therein an annular cooling chamber or 20 annular series of cooling chambers which is or are in communication with the cylinder water jacket and with the cooling space in the cylinder head, or so arranged as to permit flow of cooling fluid inside the flange. 25 The flange is adapted to seat on the upper end of the jacket wall and project above it and is clamped in position by the cylinder head, the bolts passing outside of it. Its massive cross-section adapts it to withstand 30 the clamping strain and form close joints with its head and jacket wall and makes possible the thinning of the inner chamber wall, the line of strain being through the relatively thick outer wall of the flange.

35 Referring to the drawings: the sole figure is a longitudinal section through so much of the cylinder and cylinder head as is necessary to illustrate the invention.

The cylinder therein shown is made up 40 of the cylinder jacket 1, the liner 2, and the cylinder head 3, the wall 1 terminating in an enlargement 4 against which seats the flange 5 of the liner, this flange also furnishing the seat for the cylinder head 3 with 45 provision, if desired, for the usual intermediate gasket or gaskets. Spaces 6, 7 and 8 through which cooling fluid is circulated, are provided respectively in the cylinder jacket, in the cylinder head, and in the 50 flange 5, which is hollow or chambered for that purpose so as to present annular cooling space which has also substantial extension lengthwise of the cylinder whose hottest part it surrounds, thus providing for a

sufficiently rapid and a well equalized cooling of the liner flange. The effectiveness of the chamber 8 for cooling is increased by making its inner wall 9 thinner than the wall of the liner beyond it. Space 8 is preferably placed in communication with space 60 6 by any desired number of passages 10 and with space 7 by the run-around 11 or otherwise. In order that the annular cooling chamber 8 may be readily cleaned one or more hand holes 12 having covers 13 are 65 provided in its periphery where, owing to the fact that the flange 5 extends beyond the top of the jacket wall, they are immediately accessible. The cylinder head 3 is secured to the cylinder proper by an annular series of studs 14 which surround the flange 5, being preferably spaced from it. They are received by an external stud-receiving flange or equivalent portion at the 70 end of the cylinder head remote from the cylinder and are accessible to the atmosphere, thereby promoting cooling and avoiding unequal and destructive heat strains.

Claims:

1. In an internal combustion engine, a cylinder water-jacket, a water-jacketed cylinder head having a stud-receiving flange at the end remote from the cylinder and outside the cooling space of the head, a cylinder liner having an enlarged immediately accessible external flange on the top of which the cylinder head seats and which seats on the top of the outer wall of the cylinder water-jacket, said flange being provided with an annular cooling chamber surrounding the hottest part of the cylinder and in communication with the cylinder water-jacket and external studs located outside the liner flange in the atmosphere and received by said stud-receiving flange and clamping the cylinder head to the cylinder liner and the cylinder liner to the outer wall of the jacket.

2. In an internal combustion engine, a cylinder water-jacket, a water-jacketed cylinder head having an external stud-receiving portion at the end remote from the cylinder, a cylinder liner having an enlarged immediately accessible external flange extending beyond the end of the cylinder water jacket and on the top of which the cylinder head seats and which

- seats on the top of the outer wall of the cylinder water-jacket, said flange being provided with an annular cooling chamber surrounding the hottest part of the cylinder and in communication with the cylinder water-jacket, a run-around constituting an external connection between the cooling space in the liner flange and the cooling space in the head, and external studs received by the stud-receiving portion of the cylinder head, located outside the liner flange and accessible to the atmosphere and clamping the cylinder head, cylinder liner and outer jacket wall together. 5
- 10 3. In an internal combustion engine, a cylinder water-jacket, a water-jacketed cylinder head having an external stud-receiving portion at the end remote from the cylinder, a cylinder liner having an enlarged immediately accessible external flange extending beyond the end of the cylinder water-jacket and on the top of which the cylinder head seats and which seats on the top of the outer wall of the cylinder water-jacket, said flange being provided 25 with an annular cooling chamber surrounding the hottest part of the cylinder and in communication with the cylinder water-jacket, the inner wall of the chamber being of less thickness than that of the liner wall 30 beyond it, said flange having top and bottom radially bracing cross wall adjacent the thinned part of the liner wall, thereby permitting said local thinning of the liner wall to a point less than that necessary in the rest of the liner, and external studs received by the stud-receiving portion of the cylinder head, located outside the liner flange and having parts opposite the cylinder head and parts opposite the liner flange accessible to 35 the atmosphere and clamping the cylinder head, cylinder liner and outer jacket wall together. 40

In testimony whereof, I have signed this specification.

EUGEN ZBINDEN.
